H. Hart

ATTORNEY.

UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

CUT-OUT DEVICE FOR ELECTRICAL UTENSILS.

Application filed June 4, 1919. Serial No. 301,724.

To all whom it may concern:

Be it known that I, JOSEPH F. LAMB, a citizen of the United States, and a resident of New Britain, in the county of Hartford, State of Connecticut, have invented certain new and useful Improvements in a Cut-Out Device for Electrical Utensils, of which the following is a specification.

This invention relates particularly to means for cutting off the circuit from a utensil as it approaches a dangerous degree of heat, the object being to provide a device of this sort having features of novelty and advantage.

15 In the drawings—

Fig. 1 is a sectional view through my device applied to an electrically heated utensil.

Fig. 2 is a plan view of the device.

Fig. 3 is an edge view thereof.

20 Fig. 4 is a sectional view taken on line 4—4 of Fig. 2, and

Fig. 5 is a view similar to Fig. 4 but showing a slightly different construction.

In the drawings I have shown my device applied to a cooking utensil, such as a percolator, but it is to be understood that my invention is applicable for use generally on electrically heated utensils of all kinds, the present disclosure being by way of illustration only and, therefore, it is not to be taken as restrictive of my conception.

Referring to the drawings—10 designates a percolator in the base of which is located a heating element 11 connected by means of 35 terminal wires 12 to terminal posts 13 which receive the plug, not shown, connected to the line wires. In one of the terminal wires 12 is interposed a pair of spaced apart spring blades 14 so that when 40 the gap between these blades is not bridged by the circuit closing member, the circuit to the heating element is broken.

The blades 14 together with the circuit closer and the means for controlling the 45 same are all carried by a plate 15 removably secured to the utensil 10 in any suitable manner, such as by screws 16. The advantage of this arrangement is that the device may be tested out and adjusted before it 50 is applied to the utensil so that the danger of injuring the utensil, should the device be applied thereto before it is tested, is eliminated.

The circuit closer comprises a spring 17 secured at one end to a projection or lug

18 on the plate 15 and having at its free end a circuit closing member 19 adapted to bridge the gap between the spring blades 14 when the device is in operative position. The fixed end of the spring 17 is by preference seated in a groove in the lug 18 with the edges of the spring engaging the side walls of the groove for aiding in maintaining the spring against lateral movement. The outer end of the spring may be of a reduced width to obtain the required flexibility and the circuit closing member 19 may consist of a U-shaped member insulated from the spring by a sheet of mica 20.

The means for holding the spring 17 in position to close the circuit through the heating element is, in the present illustrative disclosure, in the form of a thermostatic bar 21. In the embodiment shown in Figs. 1 to 4 inclusive, two such bars are employed, the bars being secured at one end and on opposite sides of the lug 18 by a bolt 22 or other suitable securing device.

The thermostatic bar or bars are preferably formed of two strips of metal, one of the strips 23 being a piece of steel hardened and tempered throughout its entire length and this strip is secured to the other strip 24 which may be of brass by means of rivets 25. Thus one of the strips, in the present instance the steel one 23, has a greater degree of spring action than the other strip 24 and this strip 23 being hardened and tempered the bar will not deteriorate upon a rise of temperature nor is there any danger of its setting after it is operated a number of times.

When the bars become heated, they are flexed due to the different coefficients of expansion of the strips and after they are cooled they again assume their normal straight position and, as the strip 23 is of the spring material the spring action thereof will aid in bringing the bar back to normal position more readily and quickly.

The steel strip 23 of each bar has an integral lug 26 which is inclined to the plane of the bar so as to provide an inclined surface which contacts with and rests upon a similarly inclined surface 27 on a piece 28 carried by the spring 17 and preferably secured thereto by means of a push button 29. The piece 28 has a portion lying flat against the spring and this portion has its edges upturned to form flanges 30 between

which the spring is positioned so as to prevent relative rotary movement between the piece 28 and the spring.

The piece 28 has a portion extending at right angles to the spring and, when two thermostatic bars are employed, the edges 27 at opposite sides of the spring are oppositely inclined as most clearly shown in Fig. 4. The lower end of the piece 28 is in the form of a wedge which, when the spring is forced into operative position, will cause the thermostatic bars to spread apart and allow the piece 28 to move beneath the lugs 26. It will be seen from Figs. 4 and 5 that the contacting surfaces on the lugs 26 and member 28 are inclined at an angle to the direction of movement of the spring and this arrangement is of advantage in that it provides a cam action, the force of the spring to move out of engagement with the thermostatic bar being utilized to aid in the disengagement of the parts. After the thermostatic bars have moved a slight distance upon a rise in temperature, the bar will thereafter be moved mechanically due to the pressure of the spring and the arrangement of the oppositely inclined surfaces which slide upon one another, permitting of a nicely of adjustment and assuring that the spring will be released when the temperature of the utensil to which the circuit breaker is attached reaches a predetermined point. The lug 26 being hardened, wear between the inter-engaging surfaces is eliminated and the surfaces will slide smoothly upon one another, thus providing a sensitive and delicate disengaging action of the parts.

It is an object of the present invention to prevent premature release of the circuit closer due to jarring or jolting as when the utensil to which it is attached is set down, and to accomplish this object I have provided on one side of the circuit closer, thermostatic means which may comprise the bar above described, and on the other side means engaging the circuit closer for steadyng the same. By preference, this steadyng means comprises a second thermostatic bar as shown in Figures 1 to 4 inclusive. Each of the thermostatic devices aids in preventing the spring 17 from moving laterally out of engagement with the other bar and should one of the bars, due to any cause, be accidentally moved out of engagement with the circuit closer, the other bar will maintain the spring in operative position until the temperature of the utensil reaches a predetermined degree. If desired, however, the steadyng means may comprise a fixed abutment 31, shown in Fig. 5.

It is of course obvious that my invention is susceptible of various modifications and changes which are within the spirit of the invention without departing from the scope of the following claims, it being understood

that the present disclosure of my invention is by way of illustration only and it is not to be taken as restrictive of my conception.

I claim as my invention:

1. A thermal circuit breaker having a spring secured at one end and provided at one side near its free end with an inclined surface, an electrically conductive circuit closing member carried by and electrically insulated from the free end of said spring, and a thermostatic bar extending longitudinally of and movable in a plane at right angles to the path of movement of said spring, the said thermally controlled bar having a part with a surface inclined similarly to and slidable on said inclined surface of the spring to produce cam action between said members to aid in the separation thereof.

2. A circuit breaker having an electrically conductive circuit closing member, a spring supporting the same, thermostatic means at each side of said spring, and cooperating similarly inclined parts between each of said means and the spring, the surfaces on the opposite sides of said spring being oppositely inclined.

3. A circuit breaker comprising a plate, contact blades carried thereby, a lug on said plate, a spring secured to the outer face of said lug, a circuit closing member carried by said spring and adapted to bridge the gap between said contact blades, a thermostatic bar secured to the side of said lug, and cooperating parts between said bar and spring for maintaining said spring in operative position.

4. A circuit breaker having a plate, contact blades carried thereby, a lug on the plate having a groove in its outer surface, a spring fixedly seated in said groove, a circuit closing member carried by said spring and adapted to bridge the gap between said contact blades, a thermostatic bar secured at one end to the side of said lug, and inter-engaging parts between the free end of said bar and said spring.

5. A circuit breaker having a spring secured at one end, a circuit closing member on the free end of said spring, a thermostatic bar, a member on the spring comprising a plate bent at right angles to form a portion resting against the spring and a second portion extending at right angles thereto and having a surface with which said bar engages, and a button securing said last mentioned member to said spring.

6. A circuit breaker having a spring secured at one end, a circuit closing member on the free end of said spring, a thermostatic bar, a member having a portion lying against the spring and provided with side flanges engaging the edges of the spring, said member also having a second portion at right angles to the spring and provided with a surface with which said bar engages,

and means for securing said member to the
spring.

7. A thermal circuit breaker for inter-
rupting the circuit in an electrically heated
5 utensil when said utensil becomes over-
heated and comprising a plate removably
secured to said utensil, contact blades, a cir-
cuit closing member adapted to bridge the
gap therebetween, and a pair of thermally
10 controlled members one on each side of said
circuit closing member and cooperating
therewith, said contact blades, circuit clos-
ing member and said thermally controlled
members being secured in fixed relative po-
15 sition on said plate to permit adjustment of
the circuit breaker prior to the attachment
of the plate to the utensil.

8. A circuit breaker comprising a plate,
contact blades, a lug on said plate, a spring

secured to the outer face of said lug, a cir-
cuit closing member carried by said spring
and adapted to bridge the gap between said
contact blades, a thermostatic bar secured
to each side of said lug, and cooperating
parts between said bars and spring for 20
maintaining said spring in operative position.
25

9. A circuit breaker including a projec-
tion, a spring secured to the outer face of
said projection, circuit closing means car-
ried by said spring, a flat thermostatic bar
secured to each side of said lug whereby the
planes in which said spring and bars lie are
substantially at right angles to each other,
and cooperating parts between said bars and 30
spring for maintaining the latter in opera-
tive position.
